UNITED STATES PATENT OFFICE.

GEORGE A. WESCHLER, OF BROOKLAND, DISTRICT OF COLUMBIA.

METHOD OF HEATING AND APPARATUS THEREFOR.

1,177,464.

Specification of Letters Patent. Patented Mar. 28, 1916.

Application filed February 6, 1913. Serial No. 746,636.

To all whom it may concern:

Be it known that I, GEORGE A. WESCHLER, a citizen of the United States, residing at Brookland, in the District of Columbia, have 5 invented certain new and useful Improvements in Methods of Heating and Apparatus Therefor; and I do hereby declare the following to be a full, clear, and exact description of the invention, such as will enable others skilled in the art to which it 10 pertains to make and use the same.

The present invention relates to a method of heating and the apparatus therefor and consists in combinations of steps of procedure; and combinations and arrangement of elements of apparatus necessary to the carrying out of said procedure as disclosed hereinafter and particularly set forth in the accompanying claims.

20 The purpose of the invention is to provide a means whereby to obtain the maximum efficiency of a steam heating apparatus by utilizing the heat contained in the water of condensation of the steam; and also to save 25 the cost of fuel which would otherwise be required to generate the heat thus saved.

In the present method of heating by steam, the steam pressure when it is admitted into the radiator is about 18# abs., giving 30 a temperature of about 222° F., and this steam is condensed and released from the radiator at about 200° F., when it is returned to the central heating plant by means of a vacuum pump. There is considerable 35 loss in heat from this return feed water due to the great differences in temperature between the earth which surrounds the conduit and the return water within the conduit, and this loss, of course, becomes greater the 40 greater the distance between the buildings to be heated and the central heating plant. This loss is unavoidable in most cases, as it is nearly always necessary to inject cold water into the return at the vacuum pump 45 in order to pull a good vacuum on the system. The necessity of having water at a certain temperature in order to pull a vacuum on the system, causes much waste unless the heat given off to bring the water 50 to the desired temperature can be utilized. The heat taken out during transit, and absorbed by the injection of the cold water, is consequently a needless loss.

To overcome the disadvantages mentioned 55 in the foregoing the present invention pro-

poses an apparatus disclosed in the accompanying drawings, and wherein:—

Figure 1 is a diagrammatic illustration of the apparatus complete; Fig. 2 is a side elevational view, partly in section, of a radiator *per se*; Fig. 3 is a detail view in front elevation of the central or main unit of the radiator; and Fig. 4 is a similar view showing a modified construction thereof.

Referring to the construction in detail, A 65 designates a steam radiator comprising a plurality of units connected to communicate in series through the medium of registering apertures 2, and spaced at equidistant intervals by engaging lugs 3, as with the ordinary type of radiator. A second radiator B is located immediately beneath and supports the steam radiator A and comprises a plurality of units 4 likewise connected to communicate in series through upper and 70 lower registering apertures 5 and 6 respectively. Said lower radiator is of the hot water type, while the upper radiator is of the regular form of steam radiator. The endmost units of the lower series 4 are provided with suitable legs 7 for supporting the structure. The central unit C of the upper and lower series is constructed of a single casting, and is provided with independent chambers 8 and 9 communicating respectively with the chambers of their respective adjoining series. The central radiator unit C which forms the middle section of the two united series forms a key to connect both radiators in combination as a substantial 85 single unit. This arrangement will compensate for any unequal expansion due to differences in temperature between the upper and lower radiators.

The steam pipe 10 leading from the central plant communicates with the steam radiator A and delivers the steam thereto from the central or other generating plant, and said pipe is provided with the usual 90 regulating valve 11.

A pipe 12 connects the lower portion of the upper radiator A with the upper portion of the lower radiator B; said pipe extending through the end unit of the lower series and terminating, or having its outlet 105 in the second or immediately adjoining unit thereof, as clearly illustrated in Fig. 2.

The pipe 12 is provided with a float valve comprising a casing 13 and a float 14, and which is adapted to operate in the usual 110

manner. An outlet pipe 15 connects with the lower portion of the radiator B at the end thereof opposite to that of the inlet pipe 12, and said outlet pipe 15 is provided 5 with a thermostatic valve 16 of any approved type, and which is operable to periodically release the accumulated water of condensation in the lower radiator as will be more clearly explained hereinafter.

- 10 In the operation of the apparatus, steam is admitted at an average pressure of about 18# abs. from the pipe 10 into the steam radiator A and giving about 222° F. temperature. As the heat is given off and the 15 steam condensed by radiation, the float valve (13 and 14) operates to let off such water of condensation at about 200° F., and about 18# abs. pressure. This water of condensation enters the lower radiator B through the 20 pipe 12 where the pressure is about 9.5 to 10# abs., when there is reevaporation of some of the water, due to this reduction in pressure. This second expansion of steam immediately fills, or partially fills, the lower 25 radiator giving off more heat and thus condensing again at a much lower temperature. This condensation also continues to give off heat through the walls of the radiator B until it is cooled to a temperature of about 30 135° F., at which time it will occupy the lower part of the radiator and be in contact with the thermostatic valve 16 which would be adjusted to let off water of condensation at about that temperature. This water of 35 condensation is then turned back to the power house, or central heating plant through the medium of a vacuum pump D, as shown in Fig. 1.

The return of the condensed steam, after 40 having previously utilized its contained heat, will give off less heat to the conduit or return pipe and the ground surrounding it as the differences in temperature of the ground and condensation has decreased, thus 45 deriving an increase in efficiency.

By getting more heat out of a unit weight of heating medium in one cycle, as described in the foregoing, than for a unit weight of the medium where the condensation goes 50 back at a much higher temperature will increase the efficiency. This increase is due in a great measure to the fact that the unit weight of heating medium is already in the building, and if more heat can be taken out 55 of it, than in some other conditions, there will have been saved a loss that would result from an extra transit of the unit weight of medium from the building being heated to the central heating plant, and also the loss 60 in the boiler since heat lost in transit can be replaced only by burning more fuel for

the generation of an amount of heat equivalent to that which would otherwise be lost. And further, the water returning to the boiler at a lower temperature is more susceptible to the absorption of heat; also the colder the return water the easier it is to handle with a vacuum pump which is further favorable to the use of the heating system constructed as herein shown. 70

It is obvious that those skilled in the art may vary the details of construction and arrangement of parts without departing from the spirit of my invention, and therefore I do not wish to be limited to such features except as may be required by the 75 claims.

I claim:

1. A heating apparatus comprising a source of steam supply, a radiator connected thereto and formed of two superposed sections, an upper or steam radiator section connected to said source of steam supply, and being provided with a hot water outlet, a valve casing included in said outlet, a 80 float valve mounted in said casing, and a hot water radiator section mounted below said steam radiator section, a connection between said valve casing and said hot water radiator section, an outlet pipe connected to the lower 85 portion of said hot water radiator section, and a thermostatic control valve controlling said last mentioned outlet and adapted to open when the temperature in the hot water radiator section falls below a predetermined 90 limit, substantially as described.

2. A heating apparatus comprising a source of steam supply, a radiator connected thereto and formed of two superposed sections, an upper or steam radiator section connected to said source of steam supply, and being provided with a hot water outlet, a valve casing included in said outlet, a float 100 valve mounted in said casing, and a hot water radiator section mounted below said 105 steam radiator section, a connection between said valve casing and said hot water radiator section, an outlet pipe connected to the lower portion of said hot water radiator section on the opposite side from said valve casing, 110 and a thermostatic control valve controlling said last mentioned outlet and adapted to open when the temperature in the hot water radiator section falls below a predetermined 115 limit, substantially as described.

In testimony whereof, I affix my signature, in presence of two witnesses.

GEORGE A. WESCHLER.
